[57] **CLAIM**

The ornamental design for a fluid powered hydraulic cylinder, as shown and described.

DESCRIPTION

FIG. 1 is a side plan view of a fluid powered hydraulic cylinder showing my new design;

FIG. 2 is a plan view of the opposite side thereof;

FIG. 3 is a top plan view thereof;

FIG. 4 is a front view thereof; and,

FIG. 5 is a rear view thereof.

Any undisclosed surface area in any figure is without ornamentation.
